UNITED STATES PATENT OFFICE

JOHN A. ARENZ, OF MOUNT VERNON, NEW YORK, ASSIGNOR TO DOUBLE THREAD BIT COMPANY, OF WILMINGTON, DELAWARE, A CORPORATION OF DELAWARE

AUGER BIT

Application filed May 29, 1931. Serial No. 540,944.

This invention relates to auger bits and in particular to a bit having a double threaded, single pointed, speed leading end.

A particular object of my invention is to provide a double threaded, single pointed speed bit which is equally well shaped for use in either hard or soft wood and so constructed that the auger will be fed into the wood at a uniform degree of travel and at a rate of speed much higher than at which present auger bits in use are capable of entering the material to be bored, in this way materially lessening the amount of time consumed in boring operations and lessening the cost thereof.

Another important object of my invention is to provide an auger having a single pointed speed end which is combined with a plurality of upper and lower cutting edges on the auger body so that chips are cut away cleanly and rapidly and without the use of excess power in driving the bit into the wood or material to be bored.

Another and further object of my invention is the provision of an auger bit having a screw threaded member formed on the entering end thereof which will not readily become damaged or broken during the travel of the bit through the wood and which causes the bit not only to be properly centered and to travel in a straight line after being started in the wood but also advances the auger much more rapidly than has heretofore been possible.

The foregoing and other objects of my invention will be more fully and better understood by reference to the accompanying sheet of drawing, in which,

Figure 1 is a view in elevation showing my improved form of twisted auger with which is integrally formed at its lower or advancing end, a single pointed, double threaded lead screw.

Figure 2 is a view in elevation of another type of auger bit employing a single pointed, double threaded lead screw.

Figure 3 is an enlarged view showing the double threaded, single pointed speed end of the bit as it would appear in its advance through material to be bored.

Figure 4 is an enlarged end view of the bit and lead screw illustrating the single point of the double thread made use of in its construction.

Figure 5 is a view in sectional elevation showing the use of my improved speed bit in a hole boring action, the clearance provided for the chips being clearly illustrated.

Figure 6 is a cross section taken through the bit on the line 6—6 in Figure 1 showing the unique cross sectional shape of the shank which provides greater clearance for the chips during a boring operation.

Figure 7 is a section on the line 7—7 of Figure 4.

Referring to the drawing in detail and in particular to the construction illustrated in Figure 1, 5 illustrates an auger bit, the shank or body portion 11 of which is provided at its upper end with a squared portion adapted to fit into the chuck of a brace or other turning implement. The auger bit is essentially formed from a flat strip of material twisted into a pair of spiral edges 13 and 14, the shaping of the bit being so carried out that the material between the edges, as illustrated in Figure 6, is very thin as at 15—A, the edges being flared at opposite sides to provide the cutting edges 13 and 14. It will be noted that the shank wall 15—A, being thin, provides plenty of room for the passage of chips between the section 15—A of the auger bit and the wall of the hole being bored with the result that jamming of the bit is prevented and operation of the bit is facilitated. The distance A (Figure 6) is substantially the same as the radius R, thus making the depth of the auger channels (diametrically opposite) substantially equal to half the diameter of the drill. The spiral edges 13 and 14 terminate at the lower end of the bit in a pair of horizontally extending oppositely disposed cutting blades 15 and 16 respectively, which, in turn, have formed at their outer end, vertically extending upper cutters 17 and 18 respectively and lower cutters 17—A and 18—A below said cutters 15 and 16, which serve to cut the fibers of the wood with the horizontal cut-

ters 15 and 16 which are each bevelled on one side to facilitate the cutting action.

At the lower end of the bit and formed integrally and centrally thereof, I provide 5 a screw threaded leading speed screw 22 which is substantially conical in shape and shaped to provide, as illustrated in Figure 3, the alternately spaced or double threads 19 and 20, which are so shaped that upon revolving movement of the auger bit, they will engage within the fibers of the wood which close thereover and will work their way into the wood, thus making it only necessary for the operator to revolve the auger and the lead 10 screw or barb will draw the bit through the material to be bored very rapidly and with precision. The threads 19 and 20 terminate at the lower end of the speed screw in a single point 24 which not only permits the bore to be cut straight and clean but enters the wood upon the slightest turn of the auger bit. The single point formed by the termination of the threads 19 and 20, as indicated by 15 the numeral 24 is in alignment with the longitudinal axis of the auger so that the point 24 enters the fibers of the wood and directs the auger bit in a straight line therethrough, the threads 19 and 20 drawing the auger into the wood and feeding it therethrough while 20 the cutters at the lower end of the bit remove the chips as the bit travels through the wood, it being noted that the shape in cross section of the auger permit the chips as illustrated in Figure 5 to travel out of the bore 25 without causing the auger bit to become jammed, thereby eliminating any necessity for the freeing of the bit.

With respect to the illustration of Figure 2, an auger bit is shown having a body portion 25 which terminates at its upper end also in a squared portion 26 arranged to be engaged by the socket or chuck or a brace or other turning element, this auger bit being also provided with a pair of spiral blades 27 and 28, the blades terminating in a pair of horizontally disposed cutting edges 29 and 30 respectively, positioned at opposite sides of the body of the auger 25. The cutting edges 29 and 30 are provided with side, upper 40 cutters 31 and 32 and lower cutters 31-A and 32-A respectively, the body member 25 in this instance, terminating in a double threaded speed lead screw 33 which is identical to the speed lead screw illustrated and 45 described in connection with the auger of Figure 1.

The extreme tip end of the speed lead screw 33 is provided with a single point 37 marking the termination of both threads 50 whereby a sharp wood engaging point is provided for starting the auger properly.

It will be quite evident from the foregoing that I have provided an auger bit which is double threaded, or rather, double spiral and 55 which is provided with a single point, speed

lead screw which is also double threaded, the threads being so arranged that they will draw the auger bit into the wood and thus facilitate its operation. The unique shape in cross section of the auger bit body provides a channel of maximum depth so that the chips pass rapidly up through the bit and do not retard its operation.

As illustrated in Figure 4, at one side of the bit, the end of the flanged or end portion of the bit, terminates in an upper, vertically disposed cutting edge 17 at one side of the cutting edge 15 which is generally referred to, as the horizontal cutting edge and below this horizontal cutting edge, the projection of the member 17 is also sharpened as at 17-A to provide a vertical cutting edge so that at opposite sides of the lead screw 22 there is provided three cutting edges and it is evident that the termination of each of the channels provides substantially three cutting edges at each side of the lead screw, making six cutting edges in all.

While I have described more or less precisely the details of construction, I do not wish to be understood as limiting myself thereto as I contemplate changes in the form and the proportion of parts and the substitution of equivalents as circumstances may suggest or render it expedient without departing from the spirit or scope of my invention.

Having described my invention what I claim is:—

An auger bit having a cross sectional shape presenting channels of substantially the width of half the diameter of the bit at the center of the bit, the outer edges of the channels being flared to provide cutting edges, each of said channels terminating in a horizontal cutting edge bevelled at one side thereof, the outer ends of said horizontal cutting edges being bounded by vertical cutters having cutting edges disposed above and below said horizontal cutting edge, a tapered portion terminating in a point, double threads extending to the extreme tip of the tapered portion to provide a lead screw, said threads gradually tapering out and merging in a common point, the lower end of each of the cutting edges being positioned in the center line of the screw and the meeting point of said cutting edges forming a downwardly directed point.

In testimony whereof, I have signed my name to this specification, this 27th day of May 1931.

JOHN A. ARENZ. [L. S.]
